UNITED STATES PATENT OFFICE

ALLEN M. ROSSMAN, OF WILMETTE, ILLINOIS, ASSIGNOR TO ROSSMAN, SARGENT & LUNDY PATENTS CORPORATION, OF CHICAGO, ILLINOIS, A CORPORATION OF ILLINOIS

SYSTEM AND METHOD OF REGULATION

Application filed August 28, 1930. Serial No. 472,521.

The present invention relates to a method of and means for regulation and is an improvement upon the system and method disclosed in my copending application, Serial No. 424,380, filed January 29, 1930. While the invention is particularly applicable for combustion control for steam boilers, and is so shown for illustrative purposes in this application, it is not limited to such use but is of general application.

In controlling combustion the prime desideratum is to maintain a value of combustion which is proportional to the steam or other load to be carried. The next desideratum is to do this efficiently.

As atmospheric air is substantially constant in composition and as it is the aim to maintain the efficiency of the furnace and boiler substantially constant, the amount of air required to develop the necessary heat for carrying the load is substantially directly proportional to the load. The fuel—such as powdered coal in this instance—may then be fed at a rate which will secure substantially complete and efficient union with the oxygen of the air supplied to the furnace.

The efficiency of combustion may be checked either automatically or manually, by a CO₂ meter or, after calibration of the installation, by a steam flow-air flow meter.

A steam flow-air flow meter is more convenient and prompt in operation than a CO₂ meter and I show the same as a suitable element for checking the efficiency of combustion and making adjustment of the controls accordingly, but it is to be understood that any suitable means which will determine the efficiency of combustion may be employed instead.

The air flow through the furnace is maintained by one or more forced draft fans and one or more induced draft fans. The efficient utilization of the air for supporting the combustion of the fuel depends, amongst other things, upon the ratio of the induced draft to the forced draft. If the induced draft is increased it will tend to decrease the pressure within the furnace while if the forced draft is increased it will tend to increase the furnace pressure. The furnace pressure is

therefore a function of the ratio of the induced draft to the forced draft. Hence by determining the furnace pressure, as by the use of an ordinary furnace pressure gauge or the like, the ratio of the induced draft to the forced draft may be determined, and by suitable responsive mechanism automatically maintained as desired.

The furnace and boiler may be calibrated to determine the various absolute values of air flow and coal feed to steam flow and a general or mean relation established which will be substantially correct for various loads within the range of the unit. The regulating system is then required to provide regulation for deviations from the said mean relation.

In the preferred embodiment of the present invention, as well as in the system of the above recited application, I employ variable speed drives for controlling directly the rates of fuel feed and air feed. These variable speed drives may be of any preferred form. They may be of the type shown in my Patent No. 1,830,485, issued November 3, 1931, which is the preferred form, or they may be of any of the many known forms of "Ward Leonard" variable speed control. However, insofar as the present invention is concerned any suitable variable speed control system may be used, the invention being not limited to the "Ward Leonard" system. The air feed is divided between forced draft fans and induced draft fans, each fan driven by a variable speed drive. These variable speed drives are under rheostat control and hence regulation and control are greatly simplified.

Assuming that combustion is proceeding at a fixed rate and the steam demand is increased, such increased demand will be reflected in a reduction of boiler pressure. I employ the steam pressure gauge as a master gauge to control in common the speed of the forced draft fans, the induced draft fans and the coal feeders. In place of the steam pressure gauge I may use any other means responsive to the change in load on the boiler.

The controller of my invention proportions the rate of correction to the amount of deviation in a novel and efficient manner which,

at the same time, takes care of the conflicting requirements of the furnace pressure gauge and the efficiency meter gauge.

In addition to the steam pressure gauge or other master controller, means must be provided for constantly maintaining not only the proper amount of air flow in proportion to the load on the boiler but also the ratio of the induced to the forced draft. This means must be effective independent of the boiler pressure gauge. This is desirable because the master controller effects changes according to the aforesaid means or general relation and the special controls are required to cut in when deviations from the mean are required for the sake of proper efficiency or proper coordination of the induced and forced draft fans.

In my above referred to patent the special controls cut in to the exclusion of the master control, that is, they render the master control ineffective while they are functioning to correct a deviation that may have occurred. My present system differs from that system in that here the master control is not rendered ineffective during the functioning of the special controls. An arrangement is provided whereby the master control and the special control effect two parts of a differential device which is actuated responsive to the algebraic sum of the two effects. The differential may comprise an ordinary mechanical differential wherein two of the movable members constitute drivers for the third, means being provided for preventing the transmission of a turning force from one driving member to the other. In the embodiment of my invention herein illustrated this is accomplished by actuating each of the driving members of the differential by means including an irreversible worm gear, whereby the driving member may be driven by the actuating means through the worm gear but it can not drive the actuating means, due to the fact that the worm gear is self locking and can transmit power in one direction only. The third element of the differential will obviously move at a speed and in a direction which are functions of the speeds and relative directions of operation of the driving members. This third member of the differential varies a resistance which is connected to control the speed of the fan motor, although it may be arranged to vary the speed of the motor in any other preferred manner.

Since the response of the air supply means is substantially instantaneous, or relatively prompt as compared to the response of the fuel supply means, the adjustment under the control of the efficiency meter for increasing or decreasing the rate of air supply is made to follow automatically the rate of fuel supply, and is under the control of two separate controls, namely, first the master controller, which regulates the fuel and air supply si-

multaneously, according to a predetermined ratio, and next, under the control of the efficiency meter or the like, which adjusts the air supply means independently of the master controller and simultaneously therewith. In the accompanying embodiment of my invention the efficiency meter varies the air supply to maintain the ratio of the fuel to air constant. This meter may be arranged to maintain the proper ratio by varying the fuel supply instead of the air supply.

As between forced and induced draft a relative adjustment is made, in addition to the main adjustment of the two fans made by the master controller, by means responsive to the furnace pressure which, acting upon the forced draft fan, adjusts its speed relative to the speed of the induced draft fan to maintain the proper pressure in the fire box at all times. This latter adjustment is independent of the master controller and acts whenever necessary, even though the master controller may also be acting at the same time.

In power plants wherein there is provided a plurality of furnaces the boilers of which feed to a common load, it is necessary to provide some means for regulating the distribution of the load between the respective furnaces. This regulation may be obtained by regulating the speed of operation of the coal feeding motors of the respective furnaces. In my prior application above referred to I show an arrangement whereby the speed of operation of the respective coal feeding motors of the various boilers may be automatically regulated to maintain a proper division of the load between the furnaces. In this arrangement one of the furnaces is considered as the master furnace and the others are regulated with respect to it in proportion to the respective ratio of load division between the boilers. It is one of the objects of the present invention to provide an arrangement wherein the regulation of the load between the respective boilers may take place simultaneously with the regulation of the individual boilers under the action of the special controls that maintain the individual boilers operating at their best efficiencies.

Now, to acquaint those skilled in the art with the manner of constructing and operating a system according to my invention, I shall describe, in connection with the accompanying drawings, a few embodiments of my invention.

In the drawings:

Figure 1 is a diagram of a boiler plant to which my system of regulation may be applied;

Figures 2a and 2b when placed with Figure 2b to the right of and slightly below the top of Figure 2a constitute a simplified circuit diagram of the connections for obtaining the desired regulation;

Figure 3 is a longitudinal sectional view of the differential and the mechanical driving means therefor;

Figure 4 is a top view of the differential mechanism and the driving means therefor, said view also illustrating the manner whereby the differential drives the rheostat controller;

Figure 5 is a view of the rheostat control mechanism;

Figure 6 shows a modified form of rheostat control mechanism;

Figure 7 shows a modified form of differential control mechanism wherein a single motor is used for regulating the controlling rheostat, said motor being controlled by a pair of resistors under the separate control of two sets of relays;

Figure 8 shows an arrangement wherein the differential control is obtained by counterbalancing electromagnetic forces under the control of the various regulating means; and

Figure 9 is a fragmentary circuit diagram illustrating the connections to be incorporated in the circuit of Figure 1 to provide for an automatic regulation of the load as between a plurality of furnaces.

Referring first to Figure 1, I have shown herein diagrammatically the main operating and control parts for a power generating boiler 1, which may be of any suitable type. This boiler 1 is provided with a steam pressure gauge 2 of a type suitable to operate the electrical controls hereafter to be described. The fire box 3 is shown in this case as fired with powdered coal through two sets of nozzles, 4 and 5 respectively, having individual means for supplying powdered coal thereto.

While the invention is herein shown as embodied in a steam generating plant employing powdered fuel it is to be understood that this is merely by way of illustration and not of limitation.

The furnace 3 is fed with coal and air by duplicate apparatus for each, mainly for the sake of reliability. The nozzles 4 and 5 receive their mixture of powdered coal and air through a passageway 6 from the coal pulverizer 7, this mixture being moved by the exhauster 8 driven by a suitable driving motor 9.

Fuel from a suitable source of supply is delivered by a pair of coal feeders 10-10 from the hoppers 13. The feeders 10 are driven by feeder motors 12, the speed of these motors being regulable in order to control the rate at which fuel is supplied to the boiler. This motor 12 may be a variable speed motor, for example, a D. C. motor or it may be a variable speed A. C. drive. Coal may, instead, be supplied by constant speed motors, in which event the rate of fuel feed can be varied by means of an adjustable coal gate or valve, a pilot motor being provided

for controlling the gate or valve. The pulverizer 7 has a grinding mill 14 driven by a variable speed electrical drive 15. The exhauster motor 9 may be driven at substantially constant speed although this may be a variable speed motor or drive if desired.

Primary air for carrying the pulverized fuel is supplied to the pulverizer 7 through the duct 16, this duct leading from the forced draft supply duct 17 leading from the air heater 18. A controlling damper 19, operated by a pilot motor 20 controls the air supply through the duct 16. In other words, the damper 19 regulates the primary air supply.

The nozzles 4 are fed with fuel and primary air by apparatus shown at the left of Figure 1, which is a duplicate of that shown at the right of Figure 1 and having primed reference numerals applied thereto to designate like parts.

The main air supply to the furnace 3 is furnished by a pair of forced draft fans 22 and 22', driven by variable speed drive mechanisms 23, 23'. These fans 22 and 22' deliver air through the conduits 24, 24' to the air heater 18, 18', which is heated by the exhaust gases after they pass through the economizer 25.

After the air passes out of the air heater 18 into the conduits 17, 17', the major volume of the same is delivered to the furnace 3 through the secondary air supply ducts 26, 26'. The main volume of air is supplied through the ducts 26, 26', the air supplied through the ducts 16, 16' being insufficient to support complete combustion of the fuel and serving rather as a carrier of the fuel to bring it into the furnace 3 where it mixes with the main air supply which is required to support combustion.

The products of combustion pass up through the tubes of the boiler 1 then through the economizer 25 then through the air heater 18 and thence to the conduit 27 leading to the stack 28. The conduit 27 is divided into two channels, 29, 29', leading to the induced draft fans 30, 30', which are driven at any desired speed within limit by the variable speed driving devices 32, 32' which may be of a character similar to the devices 23, 23' for driving the forced draft fans.

The pressure of air in the furnace is preferably maintained at a pressure slightly below atmospheric, generally in the neighborhood of .1 of an inch of water. The pressure prevailing in the furnace 3 is indicated upon the furnace pressure gauge 33. When the ratio of induced to forced draft is proper the above stated pressure, slightly less than atmospheric, is maintained within the furnace 3.

Obviously, in order to vary the rate of steam delivery by the boiler 1, the amount of

heat developed in the furnace must be likewise varied, assuming a constant condition of efficiency and the like in the boiler and the furnace. Such variation in developed heat means variation of the chemical union of fuel and oxygen of the air. In order to maintain efficient combustion it is necessary that the ratio of fuel to air be maintained at a proper value. Variation of the heat developed, therefore, must be accomplished by simultaneous variation of air supply and fuel supply in order to maintain the efficiency of combustion which is desired. This problem of varying simultaneously the air and fuel is, in the present instance, complicated by the necessity for maintaining the proper ratio of forced to induced draft, or vice versa.

The efficiency of combustion is determined by a carbon dioxide meter, generally termed a CO_2 meter; this is indicated at 31 as connected to the conduit 27, through which the products of combustion flow to the stack.

To obtain the best possible combustion efficiency from the boiler it is necessary to mix with the fuel as nearly as possible the correct amount of air to provide two atoms of oxygen for each atom of carbon in the fuel, or, by weight, 32 parts of oxygen for each 12 parts of carbon in the fuel. If too much air is furnished too much heat is wasted up the stack. If too little air is furnished, insufficient oxygen is supplied and not all the fuel is burned. Air in excess of the amount necessary must be supplied to insure that, so far as possible, each part of carbon comes in contact with the required two parts of oxygen. To maintain complete combustion it has been found that the amount of air supplied should be about twice the minimum amount necessary for complete combustion if all of the oxygen were to be consumed. This means that about 64 parts of oxygen, by weight, must be supplied for each 12 parts of carbon in the fuel burned. To maintain this ratio about 320 pounds of air must be furnished for each 12 pounds of carbon in the coal, or about 24 to 30 times as much air as carbon in the coal consumed. This ratio is checked by measuring the percentage of CO_2 in the flue gases, this percentage being maintained in the neighborhood of 12% to 14% under the best practicable conditions.

Instead of employing the CO_2 meter 31 as means responsive to efficiency of combustion, I may employ a meter 34 which is responsive to the ratio between steam flow and air flow. Such steam flow to air flow meters or responsive devices are known and the construction of the same forms no part of the present invention. Suffice it to say that the flow of air through the furnace may be determined by measuring the drop in pressure of the gases passing through a portion of the furnace or connections and the flow of steam delivered may be measured by means of a Pitot

tube or the like, and the two measurements compared in the meter 34 which then responds to the ratio of steam flow to air flow which, for a given fuel, should remain substantially constant, since a predetermined amount of air is required to develop a predetermined amount of steam at constant pressure.

With the boiler in continuous operation and connected to the steam main 11, for delivery of steam to a turbine or the like, the load may be assumed to be properly carried, so long as the steam pressure gauge 2 indicates that an adequate pressure is maintained. That is to say, so long as the steam pressure gauge indicates that a constant pressure is maintained, the rate of combustion is proper for the load carried by the boiler.

Any deviation of the ratio of combustion to load will be evidenced by rise or fall of steam pressure, which will at once affect the gauge 2. Therefore, with a given speed of the induced draft fans and the forced draft fans for passing a predetermined amount of air through the fire box per unit of time and with a proper setting of the coal feed 10 and damper 19 to supply the necessary fuel for union with a predetermined volume of air and the steam pressure gauge indicating the desired pressure, the boiler may be assumed to be in proper operation, carrying the load.

While the deviation from normal pressure by the master steam pressure gauge is a satisfactory load responsive device, a steam flow meter which is responsive to steam flow may be employed instead, or any other element which is responsive substantially to B. t. u. delivered by the boiler. The master pressure gauge is a simple load responsive device which fulfills the requirements of the present regulating system.

If the boiler pressure or the measurement of steam flow should drop, indicating that the rate of heat development is not as great as required, fuel and air feed should be simultaneously increased in proportion to substantially a predetermined ratio of air and fuel. This is then to be carried out by the automatic mechanism diagrammatically shown in Figure 2.

If the resultant ratio of air to fuel is not exactly right to secure the desired percentage of carbon dioxide in the fuel gases as measured by the meter 31, a correction of the ratio of air to fuel feed must be made. Also, in increasing the rate of combustion, the induced draft and forced draft must be simultaneously increased in such a manner as to maintain the furnace pressure at a proper value as determined by the furnace pressure gauge 33.

Now it can be seen that the automatic control system is called upon to vary at least three things, namely, forced draft, induced draft and coal feed, while maintaining a pre-

determined ratio between total air flow and fuel supply and between forced and induced draft, total air flow in this case being controlled by the two factors, namely, the forced draft fan 22 and the induced draft fan 30.

Reference may now be had more particularly to Figure 2 showing the system of control for the coal feed motor, the induced draft fan motors, and the forced draft fan motors. Variable rheostats 40, 41, and 42 are provided for controlling the speed of the coal feed motors, the induced draft motors, and the forced draft motors respectively. The resistances of these rheostats are varied in a manner to be presently described and they are electrically connected in any preferred form of circuits for varying the speed of the motors involved. The coal feeder motor control may be of the type shown in my above referred to Patent No. 1,830,485, to which reference may be had for a full description thereof, or they may be of the "Ward Leonard" control, or any other preferred form of speed control.

Insofar as this invention is concerned the speed of the motors may be varied in any preferred manner, not necessarily "Ward Leonard".

The resistance of the rheostat 40 is varied by a motor 45 acting through a worm 46 and a worm wheel 57. The motor 45 is connected through a variable resistance 48 and either one of two reversing switches 50 and 51 to an exciter bus 52, this bus being energized from a constant voltage direct current bus 54 through a variable rheostat 55, fuses 56, and a switch 57. Upon energization of the relays 50 or 51 to close their contacts, the motor 45 is rotated in one direction or the other, depending upon which relay was closed, and is rotated at a speed which is determined by the value of the resistance 48 and the resistance 55.

A battery bus is indicated at 63, the upper conductor of this bus being connected to the positive side of a constant voltage storage battery and the lower conductor of this bus connected to the negative side of that battery. This bus is connected through a fuse switch 62 to a pair of conductors 60 which supply potential for controlling the relays 50 and 51, as well as other relays of the system, as will be more fully pointed out as the description proceeds. The bus 63 also supplies potential through a fuse switch 65 to a master controller 66. This master controller may be of a construction such as shown in Figure 2, part 3, of the drawings in my above referred to patent, or it may be of any other approved construction. Briefly stated, this controller includes a steam pressure gauge and various instrumentalities for applying potential to one or the other of the two outgoing conductors 68 and 69 under the control of this gauge. As long as the

steam pressure remains at normal no potential is applied to either of the conductors 68 or 69. Should the steam pressure fall below normal, thus indicating that the load upon the boiler had increased, then negative potential is applied by the controller to the conductor 68, which is the increase conductor resulting, in a manner to be more fully set forth presently, in an increase in the speed of operation of the coal feed motors as well as of the induced draft and forced draft motors, thus causing the furnace to increase its output. Should the steam pressure go up, thus indicating that the furnace output was in excess of the demand upon the boilers, then negative potential is applied to the decrease conductor 69, which effects a slowing down of the coal feed motors, the forced draft motors, and the induced draft motors, all in a manner to be presently more fully set forth. Such an arrangement might cause considerable hunting unless elaborate means were taken to prevent this. The controller 66 is preferably one of a standard type now on the market and which applies the potential to the conductors 68 or 69 as the case may be by means of impulses which are of a duration or of a frequency of occurrence which is a function not only of the amount of deviation of the steam pressure from normal but also a function of the rate at which the steam pressure is varying at the moment, the term "rate" including also direction of the same.

The increase and decrease conductors 68 and 69 are connected to increase and decrease control conductors 68c and 69c, respectively, through a double pole double throw switch 72. When the switch 72 is in its lowered position the system is under control of the master controller 66. When the switch 72 is thrown to its upper position, the system may be controlled by means of a hand switch 75 which upon being depressed connects the negative battery bus through the conductor 76, 100 to the increase conductor 68c whereas the switch 75 is raised it connects the negative battery bus to the decrease conductor 69c. The common firing control conductors 68c and 69c are connected to the conductors 70 and 71 of the boiler 1 by means of a manually operable double throw switch 141. When the switch 141 is in engagement with its right hand contact, control may be exercised by the master controller 66. When the switch 120 is operated to close its left hand contact then the control is taken away from the master controller 66 and placed in the hands of a push button switch 142. When the push button switch 142 is depressed it places negative battery potential upon the decrease conductor 71, whereas when this switch is elevated it places negative battery potential upon the increase conductor 70.

Before proceeding further with the de-

scription of the control exercised by the master controller it may be well to describe the apparatus for varying the resistance of the rheostats 41 and 42 for controlling the forced draft and the induced draft. The resistance of the rheostat 41 is varied by means of a movable element 80 which is driven by either one or both of two motors 81 and 82 connected together through a mechanical differential 83. The mechanical relationship between the driving element and the driven element within the differential 83 may be as shown more particularly in Figure 3 to which reference will be had as the description proceeds. For the present it may suffice to state that the motors 81 and 82 each drive different ones of two of the elements of the differential, the third element or the spider being driven by those two elements at a speed and in a direction which is the algebraic sum of the motions imparted to the elements driven by the motors. This spider member drives the element 80 for varying the resistance of the rheostat 41. The motors 81 and 82 drive their respective differential elements through self-locking worm gears whereby neither of the motors can transmit a driving force to the other motor.

The operation of the motor 81 is controlled by a pair of electromagnetic reversing switches 86 and 87, which are adapted to cause the motor to operate in either direction, said switches connecting the motor to the constant voltage bus 54 through a fused switch 89. A variable resistance 90 is included in the motor circuit whereby the speed of the motor may be altered.

The operation of the motor 82 is under the control of a pair of electromagnetic reversing switches 92 and 93 which are adapted to cause the operation of the motor by extending a connection thereto from the exciter bus 52 by way of the conductors 95. The motor 82 is operated in one direction when the relay 92 is energized and it is operated in the opposite direction when the relay 93 is energized, the speed of operation being determined by the setting of the variable rheostat 97.

The rheostat 42 for varying the induced draft is controlled in a manner substantially identical to the control of the rheostat 41. For this purpose there is provided a movable member 100 driven by either one or both of a pair of motors 101 and 102 through a differential 103 under the control of relays 106 and 107 for the motor 101 and 108 and 109 for the motor 102. The motor 101 is controlled in the same manner as is the motor 81 and the motor 102 is controlled in the same manner as the motor 82. It is to be noted that the motors 81 and 101 are supplied with potential from the constant potential bus 54 whereas the motors 82 and 102 are supplied with potential from the bus 52, the

voltage of which is determined by the adjustment of the variable rheostat 55 that connects the bus 52 with the bus 54.

An explanation will now be given of the manner of actuating the relays 50 and 51 for controlling the coal feed motors, the relays 92 and 93 for controlling the forced draft motors, and the relays 108 and 109 for controlling the induced draft motors. All of these relays are under the control of the master controller 66. Assume that the steam pressure has gone down below normal with the result that the master controller 66, under the action of the master steam pressure gauge brings about the application of negative potential to the increase conductor 68. The application of negative battery potential to the conductor 68, which conductor is connected to the conductor 70 by way of the switch 72 (Figure 2b), results in a completion of the circuit for the winding of the relays 50, 92, and 108 for operating the pilot motors 45, 82, and 102 in a direction to bring about an increase in the speed of operation of the respective motors controlled thereby. The circuit for the relay 50 extends from the negative side of the battery, through the conductor 70, through the conductor 115 to the winding of the relay 50, thence by way of the conductor 116 to the positive side of the battery by way of the bus 60. The relays 92 and 108 are likewise connected directly across the conductor 70, which now has negative battery potential applied thereto, at the positive battery bus 60. All three of these relays operate and at their front contacts establish a circuit for the pilot motors 45, 82 and 102, said motors being supplied with potential from the exciter bus 52. The relative speeds of the three pilot motors will be determined by the particular settings of the individual pilot motor resistances 48, 97 and 120. The speeds of all three of these motors may be simultaneously varied by varying the resistance 55, a variation of which will alter the speeds of the three motors while maintaining their relative speeds substantially the same as previously. The motor 45 will vary the resistance 40 to increase the speed of operation of the coal feed motors and, assuming that the motors 81 and 101 are not operating at this time, the motors 82 and 102 will likewise effect the resistors 41 and 42 to increase the forced draft and the induced draft. The apparatus may be so calibrated as to maintain a given ratio of forced draft variation to induced draft variation during the movement of the arms 80 and 100. The value of the resistances 97 and 120 included in the circuit of the motors 82 and 102, respectively, will determine what this ratio shall be. By varying the value of the resistance 48, the speed of operation of the coal feed pilot motor 45 may be varied so as to produce a desired speed of this motor in pro-

portion to the speed of the motors 82 and 102. Reverse operation of the motors 45, 82, and 102 is brought about by the energization of the relays 51, 93, and 109, respectively, 5 said relays being energized when negative battery potential is applied to conductor 71 instead of to the conductor 70. This negative potential is applied to the conductor 71 through the master controller 66 by way of 10 the decrease conductor 69 in the event that the boiler pressure rises above a predetermined normal amount.

From the above description it may be seen that the coal feed motors 12-12 and 12'-12', 15 the forced draft motors 23 and 23', and the induced draft motors 32 and 32', all shown in Figure 1, are under the simultaneous control of the master pressure gauge 66 by way of the control conductors 70 and 71, the relative rate of operation of the respective groups 20 of motors being under individual control of the resistors 48, 97, and 120. It is also apparent from the description thus far given that these motors may all be simultaneously 25 controlled by the hand operated switch 142 upon the proper setting of the transfer switch 141, the rate of increase or decrease in the speeds of the motors being again determined by the settings of these last mentioned 30 resistors.

As previously stated, it is necessary to maintain the ratio of the forced draft to the induced draft at a certain predetermined amount in order to obtain the most efficient 35 utilization of the air used. As previously stated, the furnace pressure is a function of the ratio of the forced draft to the induced draft, this pressure going up as the forced draft is increased and going down as the induced draft is increased. I thus so employ 40 the furnace pressure gauge 33 to regulate the forced draft to maintain this ratio constant.

Assume for a moment that the total quantity 45 of air passing through the furnace per unit of time is the proper amount required for the rate of fuel combustion but that the ratio of the forced draft to the induced is improper. Let us assume that the forced draft is slightly too high and the induced draft is 50 slightly low. The furnace pressure gauge will therefore tend to slow down the forced draft fan to bring this ratio back to the normal required amount. Upon the first slight decrease in speed of the forced draft fans 55 there will be a tendency for the total quantity of air being blown through the furnace per unit time to decrease. This will change the ratio of the fuel flow to air flow. The fuel flow to air flow ratio meter 31 will therefore 60 become effective to increase the induced draft to increase the amount of air flowing through the furnace. This will also tend to bring the ratio of the forced draft to the induced draft back to normal. Therefore both of 65 these features will function at the same time

to maintain not only the ratio of the forced induced draft but also the ratio of the fuel flow to air flow. On the other hand, assume a state of affairs when the ratio of the forced draft to the induced draft is at its required amount but that there is an insufficient amount of air supplied for the amount of fuel burned. This means that both the forced draft and the induced draft must be increased to increase the rate of air flow. My improved mechanism accomplishes this result. The fuel to air ratio being too low, the efficiency meter 31 will be actuated to increase the induced draft. This will change the ratio of the forced draft to the induced draft with the result that the furnace pressure gauge 33 will be actuated to increase the forced draft at the same time that the induced draft is being increased thereby maintaining the proper ratio. It is apparent from the above description that the furnace pressure gauge 33 could be interchanged with the fuel to air ratio gauge 31 without effecting the operation of my system.

An explanation will now be given of the circuits controlled by the fuel to air ratio meter, or efficiency meter, 31 for varying the resistance 42. The movable element of this meter is adapted to be connected to the positive side of the bus 60 by means of a double-throw switch 125 and a conductor 126. When the switch 125 is closed against the right hand contact as seen in Figure 2, thereby applying the positive potential to the movable element of the efficiency meter, this movable element may energize the winding of the relay 106 at its left hand contact or the winding of the relay 107 at its right hand contact. It is to be noted that each of the windings has one end thereof connected to the respective contact controlled by the movable elements of the efficiency meter and that the other ends of the two windings are connected together and to the negative battery bus 60. The energization of either of the two relays 106 or 107 105 will establish a circuit for operating the motor 101 in one direction or the other, said circuit extending from the motor 101, through an adjustable rheostat 130, through the corresponding front contact of the particular one 110 of the two relays which is energized, thence by way of the conductors 131 and the closed switch 89 to the bus 54. The motor 101 will now operate at a speed determined by the setting of the resistance 130 and this regardless 115 of whether or not the motor 102, under the control of the master controller 66, is or is not operating. The motor 101 actuates one of the elements of the differential 103 to actuate the member 100 to regulate the resistance 120 42. When the switch 125 is in engagement with its left hand contact it places the energization of the relays 106 and 107 under the control of the hand operated switch 135, which upon being depressed places positive battery 125

potential upon the conductor connected to the winding of the relay 107, whereas upon being elevated it places this potential upon the conductor that produces the operation of the relay 106. This is provided to facilitate the hand adjustment of the rheostat 42 under the control of the motor 101.

The furnace pressure gauge 33 controls the energization of the relays 86 and 87 for controlling the motor 81 in a manner identical to the control exercised by the efficiency meter 31 over the windings of the relays 106 and 107. When the manually operable transfer switch 125 closes its right hand contact then the furnace pressure gauge and the efficiency meter 31 are both effective to automatically control the respective pilot motors 81 and 101, respectively. When the manually operable transfer switch 125 is operated to close its left hand contact control is taken away from both of these meters. Under such conditions the relays 106 or 107 may be energized by the push button 135, as previously described, whereas the relays 86 and 87 may be controlled by the manually operable push button 140. When this push button is depressed it establishes a circuit for the winding of the relay 87, whereas when this push button is raised it establishes a circuit for the winding of the relay 86. Thus, by operating the manual switch 125 to close its left hand contact, the individual pilot motors 81 and 101 may be selectively controlled by means of the respective push buttons 140 and 135.

In Figure 2b I show, in addition to the master controller, in diagrammatic form, control circuits for two additional boilers. Each of these circuits is identical to that shown in Figure 2a and therefore the major portion of the circuits has been omitted. It is sufficient to say that the common increase and decrease control conductors 68c and 69c, which extend to the control circuit for boiler No. 1, as shown in Figure 2a and previously described, also extend to the control circuits for each of the other boilers. The parts of the control system for furnace No. 2 have been given the same reference numerals as corresponding parts of the control system for furnace No. 1, the subscript 2 being added, the same arrangement being followed for furnace No. 3, the subscript 3 being added.

From the description thus far given it is apparent that the manually operable transfer switch 72 (Figure 2b) takes control away from the automatic action of the master controller 66 and transfers it to the hand switch 75 for simultaneously regulating all of the control motors of all of the furnaces; the manually operable transfer switches 141 are each effective for transferring the control of the motors that regulate any one furnace, from the master controller to the hand switch 142, which can then simultaneously control all of the regulating motors for the one par-

ticular furnace involved. The manually operable transfer switch 125 of each furnace transfers the control of the forced draft and the induced draft for that furnace from the efficiency controls 31 and 33 to the individual hand switches 140 and 135 for separately controlling the forced draft and the induced draft.

By varying the resistance 55 of the controls of furnace 1, the rate of response of all of the pilot motors of this furnace under the control of the master controller 66 may be varied. In a like manner by varying the resistances 55₂ and 55₃ the rate of response of all of the pilot motors of furnace No. 2 and furnace No. 3 under the control of the master controller may be varied. The resistances associated with each of the pilot motors, such as the resistances 48, 90, 97, 130, and 120, of Figure 2a, are provided for varying the relative rates of response of the pilot motors of any one furnace.

The system as disclosed in Fig. 2 offers an unusual degree of reliability or continuity of service. Whereas in other systems the various elements of combustion depend for their control on one actuating unit, such as a single pilot motor actuating a rheostat or damper, this system provides for two pilot motors actuating each of the draft controllers. In case of failure of either pilot motor on either of the draft controllers, the other motor on that controller will maintain substantially correct operation. For example, should the pilot motor 102 furnishing the master steam pressure adjustments to the induced draft controller 42 or either or both of its reversing switches 108, 109 fail to operate, the induced draft controller will follow changes in the demand on the boiler, under control of the efficiency responsive controller 31, which will operate through the other pilot motor 101 to maintain the correct proportion of fuel to air supply. Hence, any change in boiler demand will change the rate of fuel feed which will automatically call for a readjustment in induced draft to maintain the correct fuel/air ratio. Likewise, if the pilot motor 101 or its control, should fail to operate, the other pilot motor 102, responsive to the master controller, will continue to adjust the induced draft controller responsive to the load on the boiler, and will thereby maintain approximately a correct fuel/air balance with an occasional hand correction if the boiler demand should vary over a wide range. In the same manner either of the two pilot motors 81, 82 on the forced draft controller 41 will maintain an approximately correct setting in case the other should fail to operate. If the single pilot motor on the fuel feed controller should fail, the consequences would not be serious as the boiler would then merely continue to

operate at a constant firing rate and other boilers would carry the swings in demand.

Reference may now be had more particularly to Figures 3 and 4 wherein I show the arrangement of the differential such as 83 and the pilot motors 81 and 82 for operating the same. The arrangement of the differential 103 and of the motors 101 and 102 for regulating the induced draft is identical to that 10 for regulating the forced draft. The pilot motor 81 drives a worm 160 which in turn engages and drives a worm wheel 161. The worm and worm wheel are mounted in a gear housing 162. The worm wheel 161 is mounted 15 upon and drives a hollow shaft 163 which is journaled in suitable bearings at 164—164 and extends outside of the housing 162. The differential is indicated at 83 and one of the driving gears thereof is mounted upon 20 and keyed to the shaft 163 to be driven thereby. Suitable bearings are provided at 168 for facilitating the turning of the gear 163 with reference to the differential housing 83. The housing 83 constitutes the spider of the 25 differential as will appear as this description proceeds.

The motor 82 drives a worm 170 which in turn drives a worm wheel 171 within a gear housing 172. The gear 171 is mounted upon 30 and keyed to a shaft 173 which is journaled in suitable bearings 174—174 in the gear housing. This shaft extends into the differential casing 83, being in alignment with the shaft 163. A gear 176 is keyed to and driven by 35 the shaft 173, suitable bearings being located at 178 to facilitate turning of this gear with reference to the gear housing. A differential gear 180 is mounted upon a differential shaft 181 so as to be freely rotatable with respect 40 thereto and is in mesh with the gears 166 and 176. As long as both gears 166 and 176 are rotating in opposite directions and at the same speed, the differential shaft 181 will remain stationary. If the gears 166 and 176 45 are operating at different speed or in the same relative direction, or if one only of the gears 166 and 176 is operating, then the differential shaft 181, together with the differential casing 83, will rotate about the axis 50 of the shafts 163 and 173. The differential spindle rotates a shaft 183 that extends through the hollow shaft 163. This shaft 183 may be arranged to operate the driven element 80 (Figure 2a) that controls the 55 resistance 41. In Figure 4 I have shown a bevel gear 185 mounted upon the shaft 183, said gear meshing with a similar gear 186 that is arranged to drive an arm of a potentiometer resistance 187. The arm is indicated at 188 and is moved backwards or forward by means of a worm 189 driven by the gear 186, said arm moving over the contacts 190 and 191 for varying the resistance.

If the gear 176 is rotated by the motor 82 60 under the control of the master gauge then

the driven shaft 183 will operate at a certain speed. If, in addition, the gear 186 is also being driven in the same direction then the shaft 183 will operate twice as fast, permitting the draft change under the control of 70 the efficiency meter to actually catch up with the main control.

While I have herein shown the fuel to air ratio as being controlled by the efficiency meter 31, which is the carbon dioxide meter, 75 this control may be exercised by the efficiency meter 34 which is a meter that indicates the ratio of the steam flow to air flow. Either of these two meters will give variations which are proportional to the variations in the ratio of air flow to fuel flow since on the one hand the percentage of carbon dioxide in the flue gases is proportionate to this ratio and, insofar as the efficiency meter 34 is concerned, the steam flow is proportionate to the coal fuel flow. 80

I prefer to use an arrangement wherein the furnace pressure gauge 33 controls the forced draft whereas the efficiency meter which gives the fuel flow to air flow ratio controls the induced draft. This may, however, be reversed without departing from the spirit of my present invention since either of these two meters may be used to control one of the drafts and the other meter used to control 90 the other draft. I also propose, as an alternative, to regulate the rate of fuel flow under the joint control of the master controller and the fuel flow-air flow efficiency meter 31 or 34. In this last mentioned arrangement 95 the induced draft would therefore not be controlled by the efficiency meter. Such a control arrangement would be identical to the control arrangement shown in Figure 2a, different therefrom only in that the coal feeder 100 rheostat 40 would be controlled by an arrangement identical to that shown for controlling the induced draft rheostat 42, and the control for the induced draft rheostat would be such as is shown for the rheostat 40 in Figure 2a. Or, stated in other words, the control circuit would be exactly as shown in Figure 2a with the resistance 40 connected to control the induced draft, and the resistance 42 connected to control the coal feed 105 motors.

In Figure 6 I have shown a different well known form of controlling rheostat and a drive therefor from the shaft 183. In this instance a sprocket 195 is mounted upon and 110 driven by the shaft 183 and transmits its motion through a chain drive 196 that drives a gear 197 for turning the arm 198 of the rheostat 199.

Reference may now be had more particularly to Figure 7 wherein I show a different arrangement for controlling the resistance such as the resistance 41 or 42 of Figure 2a. In this figure the exciter bus is indicated at 115 52, the battery bus at 60, and the increase and 120

decrease firing control conductors 70 and 71, all of said conductors being connected in circuit identical to that shown in Figure 2. The increase and decrease conductors are adapted 5 to have negative battery potential applied to one or the other of the two conductors under the control of the master controller such as shown in Figure 2b. I provide a pair of increase and decrease relays 200 and 201 which 10 correspond in function to the relays 108 and 109, respectively, or the relays 92 and 93, respectively, of Figure 2. If negative potential is applied to the decrease conductor 71 then the winding of the decrease relay 201 15 is energized, whereas if negative battery potential is applied to the increase control conductor 70 then the winding of the relay 200 is energized, the circuit for energizing each of these windings being obvious. At 203 I 20 show an efficiency meter which may be the furnace pressure meter 33 of Figure 2a, or the fuel to air ratio meter 31 of Figure 2a. The movable element of this meter is connected to the positive side of the battery bus 25 and this movable element is adapted to engage either one of two contacts for establishing a circuit to the winding of an increase relay 204 or a decrease relay 205.

A pilot motor 213 is adapted to be rotated 30 in either direction by the relays 204 and 205 through a circuit including an adjustable resistance 210, and is also adapted to be rotated in either direction by the relay 200 and 201 through a circuit including an adjustable 35 resistor 217.

Assume that the increase relay 200 has operated due to the application of negative potential upon the increase conductor 70. A motor circuit now extends from the positive side of the exciter bus 52, through the conductors 214 and 215 and the back contacts of the open relays 204 and 201 to the conductor 216, from whence the positive battery potential extends through the now closed 40 middle contact of the relay 200 to the pilot motor by way of the conductor 218. From the pilot motor this circuit extends by way of the conductor 219, through the resistor 217, through the closed left hand contact of 45 the relay 200, to the conductor 220, from whence it extends to the negative side of the exciter bus over a path which extends through the closed right hand back contact of the relay 205. The pilot motor 213 will 50 now operate at a speed determined by the setting of the rheostat 217 and will vary the resistance 225 to increase the speed of forced draft motor or of the induced draft motor depending upon which motor circuit it 55 controls.

If battery potential is applied to the decrease conductor 71, the relay 201 will be operated to operate the motor 213 in the reverse direction. The circuit for the pilot 60 motor 213 extends, under these conditions,

as follows: From the positive side of the exciter bus, through the conductor 214 and the right hand closed back contact of the relay 204 to the conductor 216, thence by way of the middle front closed contact of the relay 201 and the resistance 217 to the conductor 219, thence by way of the motor 213 and the conductor 218 to the left hand front contact of the relay 201, which extends the circuit to the conductor 220. At 70 this point the circuit is completed to the negative side of the exciter bus over two paths, one of which extends through the closed right hand back contact of the relay 205 and the other of which extends the closed right hand back contact from the relay 200. From this description it is apparent that the pilot motor 213 is operated in one direction or the other over the increased and decreased conductors 70 and 71, under the control of the master controller 66 (Figure 2b) to bring about an increase or decrease of the resistance 225, which may be connected to effect the forced draft as is the resistance 41 of Figure 2a or the induced draft as is the resistance 42 of Figure 2a, or the coal feed as is the resistance 40 of Figure 2a.

The relays 204 and 205, under the control of the special control 203 are effective to establish connections to produce a rotation 95 of the pilot motor 213 in one direction or the other depending upon which of the relays is energized. In either event the circuit extends through the resistor 210. These circuits are believed to be obvious from the description thus far given and need not be repeated at this time.

A description will now be given as to the operation of the system in the event that both of the increase relays 204 and 200 are 105 operated simultaneously, or in the event that both of the decreased relays 205 and 201 are operated simultaneously. First let us assume that the increase relay 204 is operated when the relay 200 is in its operated position. The relay 200 extends positive exciter potential to the conductor 218 and negative exciter potential to the conductor 219 by way of the rheostat 217. At the same time negative exciter potential is being applied to the conductor 219 by way of the resistor 210 and the left hand now closed contact at the relay 204. The relay 204 also applies positive potential to the motor conductor 218. Since negative battery potential is now being applied to the conductor 219 by way of the resistors 210 and 217, it is apparent that these two resistors are connected in parallel and that the net effect of this is to decrease the effective resistance between the conductor 219 and the negative exciter bus. As a result the motor 213 will rotate in a direction to increase the speed of the draft fans, this pilot motor operating at a greater speed than that at which it operates when only one of the 110 115 120 125 130

two resistors 210 and 217 is included in the circuit. It is thus apparent that under these conditions the special control 203 produces an additive effect upon the motor 213 over that produced by firing control conductors acting alone.

In a like manner if both of the decrease relays 205 and 201 are closed at the same time then positive exciter potential will be applied to the conductor 219 by way of the two resistors 210 and 217 connected in parallel, the resistor 210 being connected by way of the relay 205 and the resistor 217 being connected by way of the relay 201. It is, therefore, apparent that here again the effect of operating both of the decrease relays 205 and 201 will be that the pilot motor operates at a greater speed than that at which it operates when one only of these relays is operated.

An explanation will now be given as to what will happen if the increase relay 204 under the control of the special controller 203 is operated at the time that the decrease relay 201 has been closed by the master controller 66. It is to be remembered that the motor circuit receives its negative potential by way of the conductor 220 and its positive potential by way of the conductor 216. However, when both of these relays are operated no positive potential is applied to the conductor 216 since the back contact of the relay 204 and the back contact of the relay 201 are both open. It is therefore apparent that under such a condition positive potential is not applied to either side of the motor circuit although the negative potential is applied to one side of the motor circuit by one of the relays 204—201 and to the other side of the motor circuit by the other of these two relays. Since the motor circuit is not completed back to the positive exciter bus, the motor does not operate. In a like manner if the decrease relay 205 is operated by the special controller 203 at a time that the increase relay 200 is in its operative position then again the motor circuit is not completed since the negative side of the line is open at the right hand back contact of the relay 205 and also at the right hand back contact of the relay 200. The motor 213, therefore, does not operate. This is exactly as it should be since if one of these relays tends to control the draft in a manner to increase the draft whereas the other relay tends to control the draft in a manner to decrease the same then it is apparent that no change in the draft should be made. This same action is obtained by the mechanical differential shown in Figure 2a by the subtractive action of the mechanical differential arrangement.

Reference may now be had to Figure 8 wherein I show an alternate method for controlling the pilot motor 213 of Figure 7. In this embodiment of my invention the opera-

tion of the motor 213 is controlled by an arm 260 pivoted at 261 and adapted to be swung in either direction. The direction of operation of the motor depends upon the direction of movement of the arm 260 and the speed of operation of the motor depends upon the extent of the movement of this arm. It is believed that the motor circuits will be apparent from the description thus far given. It is merely necessary to state that the arm 260 has a conducting portion 265 adapted to bridge the contact conductors 266—267 or 266'—267' and has another conducting portion 268 insulated from the portion 265 for establishing a bridging connection between the inner resistor and the inner circular contact segment. The arm 260 is adapted to be swung in one direction by either one of two electromagnetic coils 280 and 281, and is adapted to be swung in the other direction by either one or both of two electromagnetic coils 282 and 283. The coils 280 and 282 are controlled over the increase and decrease conductors 70 and 71, respectively, and correspond to the windings of the relays 200 and 201 of Figure 7. The coils 281 and 283 are adapted to be controlled by the movable element of the gauge 203 which may correspond to the gauge 33 of Figure 2a or to the gauge 31 of this same figure. Adjustable regulating resistances are provided in the circuits of the respective coils 280 to 283 for regulating the effects of these coils. Springs 285—285 are provided for returning the arm 260 to its neutral position. If one of the two coils on one side of the arm 260 or one of the coils on the other side of the arm 260 is energized then this arm will be swung one direction or the other to a certain extent. If both of the coils on one side of the arm or both of the coils on the other side of the arm are simultaneously energized then this arm will swing in the corresponding direction by a greater amount, thus causing a greater speed of operation of the pilot motor 213. If two relay windings on the opposite sides of the arm 260 are simultaneously energized then the arm will not be moved in either direction. That this is the desired operation is believed to be apparent from the preceding description.

While in Figure 1 I have shown a furnace wherein the forced draft and the induced draft are both produced by variable speed motors, these drafts being varied by varying the speed of the motors, the variation in the draft may be produced in different manners. For instance, the forced draft fans and the induced draft fans may be driven by constant speed motors and the effect of the fans may be varied by damper control. If damper control of the air flow is used then the movable element 80 of Figure 2a, and the movable element 100 of this same figure, control the dampers for the forced draft and the in-

duced draft, respectively. This control may be exercised through a direct mechanical connection or through a pilot motor. If the regulating means shown in Figures 7 or 8 is used then the pilot motor 213 may be arranged to control the extent of damper opening.

By means of the system thus far described an adjustment of the firing rate and air flow 10 for each boiler may be accomplished. Now it frequently occurs that it is desirable to fire one of the boilers at a reduced rate as compared with another. If the total load is increased, it will be apparent that one of the 15 boilers may be fired at an increased rate to take care of the increased load, or all of the boilers may be fired at a proportionately increased rate to carry the increased load while maintaining the proportionate loading between the boilers. In order to maintain a proportionate loading upon all of the boilers at all times, it is necessary, or at least desirable, to provide some sort of regulating means for maintaining the proportionate 20 loading on the respective boilers in the event that a variation in the relationship of the loads carried by the respective boilers should occur.

I consider that the most effective way to 30 handle the situation is that so long as changes in load are relatively minor as compared with the total load capacity, such changes and demand should be met by a proportionate change in the rate of firing of all of the boilers operating together. For the purpose of proportioning the load, one boiler is assumed to be a master boiler and the load of the others is adjusted relative to it. Then, for variations in load, the entire group is fired more 40 or less to meet the variations in demand.

In order to maintain the highest degree of efficiency of the respective boilers, it is desirable that each boiler should remain under the control of its individual special efficiency 45 control at all times, even though regulation may be taking place for proportioning the loads on the respective boilers.

In Figure 9 I show an arrangement for maintaining at all times, the desired proportionate loading of the respective boilers. The automatic load division maintaining means is adapted to be included in the system shown in Figure 2a, and I have shown, in Figure 9, as much of the system of Figure 50 2a as is deemed to be necessary for an understanding of the manner of connecting the automatic load division maintaining means in the system shown in Figure 2a. Corresponding parts of Figures 9 and 2 have been given corresponding reference numerals.

Since the rate of firing is that of the rate of coal feeding, and the rate of coal feeding in my system is dependent upon the potentials impressed upon the armature circuits of the 55 coal feeder motors, it is possible to maintain

any desired ratio of feeding, and that can be done by maintaining the corresponding ratio of voltages upon the coal feeder motor armature circuits.

In Figure 9 I have shown, in diagrammatic form, the coal feed motor circuit arrangement. This includes a motor generator set 300 comprising a constant speed alternating current motor 301 driving a direct current generator 302 having a field 303 under the control of the resistance 40, which resistance is varied as shown in Figure 2. This generator supplies variable potential for operating the coal feed motors 12 at the desired speed. The speed of the motors 12, hence the rate of firing of the boiler 1, will be determined by the voltage of the generator 302, and by comparing this voltage with the voltage of similar generators of the different boilers a comparison of the firing rates of the respective boilers may be had. For this purpose a set of conductors 308 extend the potential of the generator 302 to a set of conductors 310. The voltage on the conductors 310 controls suitable instrumentalities, as will now be explained, for automatically maintaining the relation of firing rate of one boiler with respect to the other boilers.

In order to automatically maintain the relation of the firing rate of one boiler with respect to the other boilers I provide each boiler control system with a differential relay 315. Each of these differential relays comprises a pair of coils, 316 and 317, the coil 316 being connected to the coal feeder bus 310 of boiler No. 1 so as to be energized in proportion to the voltage on said bus, which is therefore in proportion to the rate of firing of boiler No. 1. In series with the coil 316 I provide an adjusting rheostat 318 for regulating the current flow through this coil, for the purpose of maintaining a balanced relation between the voltage of the bus 310 and that of the load balance bus 320 to which the coal feeder potential bus of any one of the boilers may be connected. Assume that boiler No. 2 is connected to the load balance bus 320, as indicated by the plug switch 321, and assume further that the potential upon the coal feeder potential bus 308 is the full potential corresponding to the normal firing rate. The rheostat 318 which is connected in series with the winding 316 is so adjusted that the predetermined lower voltage on the bus 310, acting through the voltage differential relay winding 316 will just balance the normal voltage applied to the winding 317 acting through a series resistance 323, the less resistance 318 connected in circuit the lower will be the firing rate of the corresponding boiler No. 1.

The coils 316 and 317 operate upon a balance member having a movable contact 324 and adapted to engage a contact upon its right hand side or a contact upon its left hand

side to increase or decrease the rate of firing of the boiler. These contacts control the circuits of an increase cut-in relay 325 and a decrease cut-in relay 326. It is to be noted that the circuit from the common increase and decrease firing control conductors 68c and 69c extend through back contacts on the relays 325 and 326 to the contacts of the switch 141. In the circuit shown in Figure 2a the conductors 68c and 69c lead directly to the contacts of the switch 141 instead of through contacts of relays such as the cut-in relays 325—326. It is thus apparent from the circuit shown in Figure 9 that the energization 15 of either of the two cut-in relays 325 or 326 will interrupt the control by the master controller over the particular boiler involved and will substitute therefor the control by the differential relay 315 which controls the relays 20 325 and 326. Upon energization of the relay 325, negative potential is applied from the negative side of the conductors 60 by way of the conductor 328 and the lower front contact of the relay 325 to the conductor 329, which 25 extends the potential by way of the switch 141 to the increase firing control conductor 70. In a like manner upon the energization of the relay 326, the negative potential is applied by way of the lower front contacts of 30 this relay to the conductor 330 and thence by way of the switch 141 to the decrease firing control conductor 71.

The windings 317 of each of the differential relays 315 are connected in parallel by way 35 of the set of conductors 320. The set of conductors 320 is adapted to have applied thereto a voltage which is equal to the voltage applied to the firing motors of any one of the boilers as determined by the setting of the 40 plug switch 321, which may be located as shown in Figure 9 or may be located to establish connections between the contacts 340 or the contacts 341. As shown, boiler No. 2 constitutes the master boiler and the load division 45 is made with reference to the load on this boiler. The potential applied to each of the right hand windings of the differential relays 315 of the respective boilers is proportionate to the voltage applied to the firing motors of 50 boiler No. 2, whereas the potential applied to the left hand windings of each of the relays 315 is proportionate to the voltage applied to the firing motors of the respective individual boilers. Now, if through any difference 55 in rate of response of, for example, the rheostat adjusting motor 45 of boiler No. 1, which motor controls the firing rate of this boiler, the rate of feeding of one of the coal feeders tends to vary from the predetermined 60 ratio with respect to the master boiler there will be a corresponding variation in voltage of the generator 302. The voltage differential relay therefore becomes unbalanced and through its load division relays 325 or 326 as 65 the case may be cuts into the local firing con-

trol wires of the particular boiler and adjusts the rate of firing accordingly. As soon as this regulating adjustment has been made, the voltage differential relay tends to balance and the operation proceeds in the proper relation. The control exercised over the conductors 70 and 71, of Figure 9, is obtained through apparatus and circuits such as shown in Figure 2. It is to be noted that during the time that the firing of one of the boilers is being adjusted by the action of the differential relay 315, the individual controls 31 and 33 of Figure 2 still retain control and maintain the proper fuel to air ratio and forced draft to induce draft ratio of the boiler being regulated. As a result of this simultaneous action, the tendency to hunt is materially decreased, if not entirely eliminated.

In compliance with the requirements of the patent statutes I have herein shown and described a preferred embodiment of my invention and the method of operation of the same. It is, however, to be understood that I am not limited to the precise details herein shown, the same being merely illustrative. What I 90 consider new and desire to secure by Letters Patent is:

1. In combination, a furnace, means for producing a draft in the furnace, means controlled responsive to the occurrence of an increase or a decrease of the furnace pressure from a predetermined normal for producing a continuous motion tending to bring about a corresponding change in the draft to correct the furnace pressure, means responsive to the occurrence of an increase or a decrease in the heat demand on the furnace from a normal amount for producing a continuous motion tending to bring about a corresponding change in the draft, means actuated in accordance with the instantaneous extent of the two motions for effecting the change in the draft, and means for adjusting the relative extents of the two motions.

2. In combination, a furnace, a boiler heated thereby, means for producing a draft in the furnace, switching means controlled responsive to the occurrence of an increase or a decrease of the furnace pressure from a predetermined normal separate switching means responsive to the occurrence of an increase or a decrease in the boiler pressure from a normal amount, differential means actuated in accordance with the instantaneous actuation of the two switching means for effecting a change in the draft and means for adjusting the relative actuation of the two switching means.

3. In combination, a furnace, means for producing a forced draft and an induced draft in the furnace, means controlled responsive to the occurrence of an increase or a decrease of the heat demand on the furnace from a predetermined normal for producing a continuing motion tending to bring about a cor-

responding change in both the forced draft and in the induced draft, means responsive to the occurrence of an increase or a decrease in the relation of the forced draft to the induced draft from a predetermined normal for producing a continuing motion tending to bring about a corresponding change in at least one of the drafts to correct the relation, means actuated in accordance with the instantaneous extent of the two motions for effecting the change in the last mentioned draft and means for adjusting the relative extents of the two motions.

4. In combination, a furnace, a boiler heated thereby, means for producing a forced draft and an induced draft in the furnace, switching means controlled responsive to the occurrence of an increase or a decrease of the ratio of the forced to the induced draft from a predetermined normal, switching means responsive to the occurrence of an increase or a decrease in the boiler pressure from a normal amount, differential means actuated in accordance with the instantaneous actuation of the two switching means for effecting the change in the draft, and means for adjusting the relative actuation of the two switching means.

5. In a system of the class described, a furnace, air supply means for said furnace, a controller therefor, having electric motor governing means responsive to the demand upon the furnace, electric motor governing means responsive to the efficiency of combustion and means for combining the simultaneous actions of said governing means and applying a governing action on said controller at a rate which is a function of the resultant of the two governing actions.

6. In combination, a boiler, a pressure gauge therefor, a furnace for the boiler, a fuel feeder for the furnace, a rheostat for controlling the speed of the fuel feeder, a motor for adjusting said rheostat, air supply means, a rheostat for controlling the speed of the air supply means, a motor for adjusting said second rheostat, a pair of firing control wires for governing the operation of said motors under the control of said gauge, an efficiency meter for the furnace, and means for placing the second motor under the additional control of said efficiency meter so long as said meter indicates abnormal efficiency, while maintaining the same under control of the pressure gauge.

7. In combination, a boiler, a steam pressure gauge therefor, a furnace for the boiler, a fuel feeder for the furnace, a rheostat for controlling the speed of the fuel feeder, a motor for adjusting said rheostat, air supply means, a rheostat for controlling the speed of said air supply means, a motor for adjusting said second rheostat, a pair of firing control wires for governing the operation of said motors under the control of said gauge, a

furnace pressure gauge and a means for placing the second motor under the simultaneous joint control of both of said gauges, said last named means including means for adjusting said second motor at a rate which is a function of the two governing actions.

8. In combination, a boiler, a steam pressure gauge therefor, a furnace for the boiler, a fuel feed for the furnace, a variable speed motor for the fuel feed, a rheostat for the motor and electrically controlled adjusting means for the rheostat, an air supply means, a variable speed motor for the air supply means, a rheostat for said last named motor, electrically controlled adjusting means for said second rheostat, rheostats for controlling the relative rates of response of said two adjusting means, means under the control of the gauge for operating said two adjusting means simultaneously, an efficiency meter for the furnace, and means under the control of the efficiency meter for individually controlling the second adjusting means simultaneously with the control thereover by the gauge.

9. In combination with a furnace including variable induced draft means, variable forced draft means and variable fuel feed means, a controller for each of said variable means, motor means controlled by the load for regulating the controllers for each of the draft means, motor means controlled by the load for regulating the controller for the fuel feed means, additional motor means for regulating the controller for one of said variable means in accordance with the variation in the efficiency of combustion, said additional means being independent of the corresponding first mentioned draft controller regulating motor means whereby in the event of failure of either of said draft regulating motor means the other said means maintains the draft regulation.

10. In combination with a furnace including variable induced draft means, a controller therefor, variable forced draft means and a controller therefor, motor means controlled by the load on the furnace for regulating the controllers for each of the draft means, and additional motor means for regulating the controller for one of the draft means in accordance with the variation in the furnace pressure, said additional means being independent of the corresponding first mentioned draft controller regulating motor means whereby in the event of failure of either of said draft regulating motor means the other said means maintains the draft regulation.

11. In combination with a furnace including fuel feeding means, variable induced draft means, variable forced draft means, separate pilot means for varying the two draft means, each of said pilot means including two sets of current reversing means for exercising control thereover, a master device for controlling the fuel feeding means and

- for simultaneously controlling both of the draft means, each through one of its sets of reversing means, gauges for controlling the other sets of reversing means of the two pilot means, said gauges being responsive to variations in the relationship of forced draft to induced draft and of air flow to fuel flow, whereby full regulation of the forced draft and the induced draft is maintained even in the event of failure of either set of reversing means, of either draft control pilot means and adjustable means for setting the relative rates of actuation of said reversing means.
12. In combination with a furnace including fuel feeding means, variable induced draft means, variable forced draft means, separate pilot means for varying the two draft means, each of said pilot means including two sets of current reversing means for exercising control thereover, a master device for controlling the fuel feeding means and for simultaneously controlling both of the draft means, each through one of its sets of reversing means, gauges for controlling the other sets of reversing means of the two pilot means, said gauges being responsive to variations in the relationship of forced draft to induced draft and of air flow to fuel flow, whereby full regulation of the forced draft and the induced draft is maintained even in the event of failure of either set of reversing means, of either draft control pilot means and adjustable means for setting the relative rates of actuation of said reversing means.
13. In combination, a battery of boilers, a load responsive device common to the battery, a fuel feed device, a variable speed motor, a variable speed motor therefor, governing means for controlling the speed of said motor, an air supply device, a variable speed motor therefor, governing means for said second motor, a pair of adjusting means for said pair of governing means, load apportioning means for controlling the relative rates of operation of one pair of adjusting means for one boiler with reference to the rate of operation of another pair of adjusting means for another boiler, a master controller controlling placing the adjusting means of all the boilers in common, load apportioning means for comparing the loads carried by the respective boilers, the adjusting means of each boiler being also under the control of said load apportioning means, and means for each furnace responsive to the efficiency of combustion, said adjusting means for controlling the air supply device of each furnace being also subject to the control of said efficiency responsive means of the respective furnaces simultaneously with the other controls exercised thereover.
14. In combination, a furnace, a boiler heated thereby, a fuel feeding device, a reversing means, gauges for controlling the other sets of reversing means of the two pilot means, said gauges being responsive to variations in the relationship of forced draft to induced draft and of air flow to fuel flow, whereby full regulation of the forced draft and the induced draft is maintained even in the event of failure of either set of reversing means, of either draft control pilot means and adjustable means for setting the relative rates of actuation of said reversing means.
15. In combination, a furnace, a boiler heated thereby, a variable fuel feeding means, a variable induced draft means, a variable forced draft means, controllers for each of the said means, at least two of the controllers being adjusted each by means of two motors connected to the controller through a differential gear in such a manner that either or both motors can effect adjustments on the variations in the relationship of forced draft to induced draft and of air flow to fuel flow, whereby full regulation of the forced draft and the induced draft is maintained even in the event of failure of either set of reversing means, of either draft control pilot means and adjustable means for setting the relative rates of actuation of said reversing means.
16. In a combustion system, three separate control means each for controlling one of furnaces for said boilers, each furnace having a fuel feed device, a variable speed motor therefor, governing means for controlling the speed of said motor, an air supply device, a variable speed motor therefor, governing means for said second motor, a pair of adjusting means for said pair of governing means, load apportioning means for controlling the relative rates of operation of one pair of adjusting means for one boiler with reference to the rate of operation of another pair of adjusting means for another boiler, a master controller controlling placing the adjusting means of all the boilers in common, load apportioning means for comparing the loads carried by the respective boilers, the adjusting means of each boiler being also under the control of said load apportioning means, and means for each furnace responsive to the efficiency of combustion, said adjusting means for controlling the air supply device of each furnace being also subject to the control of said efficiency responsive means of the respective furnaces simultaneously with the other controls exercised thereover.
17. In a combustion system, three separate control means each for controlling one of the factors of combustion and each including a pilot motor, means responsive to predetermined conditions for simultaneously actuating all of the motors, two of said control means including additional pilot motors, means responsive to relative variations in two combustion factors for actuating one of the additional motors, and means responsive to the pressure in the fire box for governing the operation of the second motor of the controller of one of the draft means, and the master device during the normal operation of the system, and adjustable resistances for setting the relative rates of actuation of said reversing means.
18. In a combustion system, three separate control means each for controlling one of the factors of combustion and each including a pilot motor, means responsive to predetermined conditions for simultaneously actuating all of the motors, two of said control means including additional pilot motors, means responsive to relative variations in two combustion factors for actuating the other additional motor, each of said two last mentioned control means having a differential actuated by both of its motors and including a controlling element controlled in accordance with the instantaneous velocities of both of its motors.
19. In a combustion control system, three separate control means each for controlling one of the factors of combustion and each including a pilot motor, means responsive to predetermined conditions for simultaneously actuating all of the motors, two of said control means including additional pilot motors, means responsive to relative variations in two combustion factors for actuating one of the additional motors, means

responsive to relative variations in two other combustion factors for actuating the other additional motor, each of said two last mentioned control means having a differential actuated by both of its motors and including a controlling element controlled in accordance with the instantaneous velocities of both of its motors, and variable pre-set resistors individual to the respective motors for predetermined the speed of operation thereof.

18. In a combustion control system, three separate control means each for controlling one of the factors of combustion and each including a pilot motor, means responsive to predetermined conditions for simultaneously actuating all of the motors, two of said control means including additional pilot motors, means responsive to relative variations in two combustion factors for actuating one of the additional motors, means responsive to relative variations in two other combustion factors for actuating the other additional motor, each of said two last mentioned control means having a differential actuated by both of its motors and including a controlling element controlled in accordance with the instantaneous velocities of both of its motors, variable pre-set resistors individual to the respective motors for predetermined the speed of operation thereof, and a variable pre-set resistor in common to the three first mentioned pilot motors for simultaneously variably pre-adjusting the speed of all three of those motors with respect to the pre-adjusted speed of operation of the other two motors.

19. A combustion control system comprising means for maintaining one of the conditions of combustion, other means for maintaining another condition of combustion, separate normally inoperative pilot motor means for controlling the respective maintaining means, means responsive to predetermined conditions for actuating one of the pilot motor means at a predetermined fixed speed and including an adjustable rheostat for predetermined the speed, means responsive to other predetermined conditions for actuating the other pilot motor means at a predetermined fixed speed and including a different adjustable rheostat for predetermined the speed, and common control means responsive to other predetermined conditions for actuating the two pilot motor means at predetermined fixed speeds and including separate adjustable rheostats for separately predetermined the speeds of the two pilot motor means independent of the adjustment of the first mentioned rheostats.

20. A combustion control system comprising means for maintaining one of the conditions of combustion, other means for maintaining another condition of combustion, separate normally inoperative pilot motor

means for controlling the respective maintaining means, means responsive to predetermined conditions for actuating one of the pilot motor means at a predetermined fixed speed and including an adjustable rheostat for predetermined the speed, means responsive to other predetermined conditions for actuating the other pilot motor means at a predetermined fixed speed and including a different adjustable rheostat for predetermined the speed, and common control means responsive to other predetermined conditions for actuating the two pilot motor means at predetermined fixed speeds and including an adjustable rheostat for predetermined the speeds of the pilot motor means under the action of the last named means, said last mentioned rheostat being in a circuit separate from the circuits of the first named rheostats.

21. In combination with a pair of control devices each including pilot motor actuated means, means individual to each device for controlling said pilot motor means and including individual adjustable rheostats for adjustably fixing the relative speeds of said pilot motor means when actuated by said individual means, means common to said devices for controlling said pilot motor means and including separate rheostats for adjustably fixing the relative speeds of said pilot motor means when actuated by said common controlling means, and means effective responsive to the control of a pilot motor actuated means by both of its controlling means for actuating the pilot motor means at a speed which is a resultant of the two adjustably fixed speeds.

22. In combination with a pair of control devices each including pilot motor actuated means, means individual to each device for controlling said pilot motor means and including individual adjustable rheostats for adjustably fixing the relative speeds of said pilot motor means when actuated by said individual means, means common to said devices for controlling said pilot motor means and including separate rheostats for adjustably fixing the relative speeds of said pilot motor means when actuated by said common controlling means, a rheostat in common to both of the pilot actuated means for simultaneously adjusting the speed at which both actuating means will operate when actuated by one of its controlling means, and means effective responsive to the control of a pilot motor actuated means by both of its controlling means for actuating the pilot motor means at a speed which is a resultant of the two adjustably fixed speeds.

23. In combination with a differential including two driven elements and a driving element, a pair of pilot motors for driving the driven elements, means for effecting independent operation of said motors each at

- substantially constant predetermined speeds, and means comprising separate adjustable rheostats in the respective motor circuits for establishing the predetermined speeds.
- 5 24. In combination with two control devices each including a pair of pilot motors; means individual to each control device for actuating one of the associated motors; means common to the two control devices for simultaneously actuating the other motor of the two devices; separate adjustable rheostats associated with the respective motors for adjustably fixing their respective speeds, and a single adjustable rheostat for simultaneously adjusting the speed of the two motors that are controlled by said second named means. 70
- 10 25. In combination a set of pilot motors, means for controlling said motors in parallel, separate adjustable rheostats for adjusting the relative speeds of the motors, a separate set of pilot motors and means individual to those motors for separately controlling them and including adjustable rheostats for adjusting their relative speeds, an additional rheostat in common to the motors of one set for adjusting the relative speeds of the two sets of motors, an adjusting device actuated by two motors one from each set, and another adjusting device actuated by the other motors of the two sets. 75
- 15 26. A pilot motor, separate circuit connections each including a rheostat for adjustably fixing the speed of operation of the motor and means for establishing forward and reverse operating connections for the motor, means opening the motor circuit responsive to the simultaneous operation in the two circuits of opposite operation establishing means, and means for connecting both rheostats in circuit to increase the motor speed responsive to the simultaneous operation in the two circuits of like operation establishing means. 80
- 20 27. In a control system, a differential relay having a movable element movable in either direction from a normal position, means controlled responsive to predetermined conditions for moving said element in either direction a predetermined fixed amount, said means including operating windings and variable resistor means for variably fixing said predetermined amount of movement, additional means responsive to other predetermined conditions for variably moving said element a predetermined fixed amount, said last means also including variable resistor means for variably fixing said amount of movement, a pilot motor, and means for actuating said motor in accordance with the extent of actuation of said element. 85
- 25 28. In combination with a control device for regulating the rate of supply of an element of combustion to a furnace including pilot motor actuating means, means responsive to one set of conditions variable in the operation of the furnace for effecting operation of said actuating means at a predetermined rate of speed, means responsive to a second set of conditions variable in the operation of the furnace for effecting operation of said actuating means at a second predetermined rate of speed, and means for adjusting the ratio between said predetermined rates of speed. 90
- 30 29. In combination with a control device for regulating the rate of supply of an element of combustion to a furnace including an electric pilot motor, a plurality of controlling means for controlling said pilot motor at separately predetermined speeds, each of said controlling means being responsive to a given set of variable conditions in the operation of the furnace, and rheostat means for adjustably setting each of said predetermined speeds. 95
- 35 In witness whereof, I hereunto subscribe my name this 21st day of August, 1930.
- 40 ALLEN M. ROSSMAN.
- 45 27. In a control system, a differential relay
